PRE-INSTALLATION ASSEMBLY FOR SWING-UP DOORS

David M. Robinson, New Britain, Conn., assignor to The Stanley Works, New Britain, Conn., a corporation of Connecticut

Application January 16, 1956, Serial No. 559,299

5 Claims. (Cl. 206—46)

This invention relates to swing-up doors of the unarticulated type which are adapted to swing upwardly from a closed vertical position in a doorway to an open horizontal position. The invention is directed more particularly to a pre-installation assembly of the mounting and fastening means including the track for such a door whereby the handling and shipping of the parts and the installation of the door is greatly simplified.

The various individual parts and mechanisms for mounting a swing-up door of the unarticulated type are available commercially, but, inasmuch as these elements are many in number and of various shapes and sizes, there is presented a considerable problem of packaging and shipping and identifying an assemblage or collection of all of the parts and mechanisms required for a single installation. There is presented a further considerable problem in that some of the parts have to be mounted on the door, some on the door jamb and some on the ceiling in precise order and relationship to each other and the parts have to be interconnected for proper operation. The result is that detailed and difficult instructions are required for the inexperienced user and even professionals have difficulty in identifying and placing the parts in proper relationship, which frequently requires considerable time and the services of at least two men.

It thus is an object of the present invention to provide a pre-installation assembly of the mounting and fastening means for a swing-up door which can be shipped as a unit and which serves as its own template during attachment to the door and adjacent building structure. Included in this aim is the provision of a pre-installation assembly which is self-supporting for packaging and shipment, which can be installed in a simple and easy manner with a minimum of instruction, and which will inherently result in a proper placement and space relationship of the parts during assembly.

Other objects will be in part obvious, and in part pointed out more in detail hereinafter.

The invention accordingly consists in the features of construction, combination of elements and arrangement of parts which will be exemplified in the construction hereafter set forth and the scope of the application of which will be indicated in the appended claims.

In the drawings:

Figure 1 is a front elevational view of a pre-installation assembly of the mounting and fastening elements of a swing-up door assembled in accordance with the invention;

Figure 2 is a side elevation of the assembly of Figure 1;

Figure 3 is a sectional view along the lines of 3—3 of Figure 1;

Figure 4 is an enlarged fragmentary view of a portion of the elements of Figure 1 when partially installed;

Figure 5 is an enlarged fragmentary view of another portion of the elements of Figure 1 when partially installed; and

2

Figure 6 is a fragmentary perspective view of the final installation.

For simplicity and brevity of presentation, there is shown in the drawings only the pre-installation assembly of parts for the right-hand side of the door. It will be understood that in actual practice a similar pre-installation assembly will be provided also for the left-hand side of the door.

10 In accordance with the invention, the parts are held together for shipping and installation by the track 10 which in the final installation is attached horizontally to the ceiling. As shown in the drawings, the track 10 is channel-shaped in cross section and has a length at least as long as the height of the door with which it is to be used. Since the track is made of steel and is of rugged design, it provides a very satisfactory rigid frame for the pre-installation assembly.

15 Located at the upper end of the track, as viewed in Figs. 1, 2 and 4, and pivotally connected thereto at 11 is a track mounting bracket 12 which in the final installation is used to connect the track to the upper end of the door jamb. At approximately the center of the track and rigidly connected thereto in spaced relationship by a spacer block 13 and bolt 14 (see Fig. 3) is a jamb 20 bracket 15 for attachment to the door jamb which has a first flange 16 forming an anchor at 17 for the counter-balance spring 18 and a second flange 19 for a support for the bearing 20 to which is connected the door arm 21. The free ends of the spring 18 and door arm 21 are held 25 in the position shown in Figs. 1 and 2 by a spacer block 22 situated between the arm 21 and track 10 and a tape 23 tightly wrapped around all the parts. The lower end of arm 21 is pivotally connected to an arm supporting bracket 24 which also carries a latch 25.

30 Secured to the jamb bracket 15 is an elongated metal jamb plate 30 having a series of apertures 31 through which screws may be inserted to attach the plate to the door jamb. A plurality of vertically aligned struck-in ears or tabs 32 are provided as guides whereby the plate 35 may be properly located with respect to the edge of the door jamb. The upper end of the jamb plate has an outwardly bent flange 33 to which is bolted by bolt 34 and nut 35 in slightly off-set relationship the lower outwardly flanged end 36 of an elongated metal door plate 37. The door plate 37 is similar to jamb plate 30 except that it has apertures 38 along its left-hand side for receiving screws by which it may be attached to the door and its inwardly struck ears or tabs 39 serve as locating elements for engaging the side edge of the door.

35 The upper end of the door plate 37 has an inwardly extending flange 40 for engaging the top edge of the door. Also, there is secured to the upper end of the door plate 37 a wheel bracket 41 which carries a rotatable wheel 42 which in turn is inserted within the upper end of the track 10. Since the wheel 42 and track 10 are 40 so dimensioned that they cannot separate laterally, it will be appreciated that the upper ends of the parts of the pre-installation assembly are thus effectively secured together.

45 The pre-installation assembly as just described, having all parts interconnected and attached to the horizontal track, is thus inherently rigid and stable and can be stored and shipped without damage or the need for special packages or packaging for the individual parts. Of course, an outer covering of wrapping paper or a carton may be added, if desired, to keep the parts clean or for convenience of handling.

50 The installation of the assembly thus described on a door is an exceedingly simple and easy operation. Assuming that a door as indicated at 50 has been placed in the door opening and properly blocked into position, the first step is merely to take the pre-installation assembly of

Figs. 1 and 2 (after removal of any outer wrapping) and hang it in place on the door. This is done simply by engaging the upper flange 49 on the top edge of the door and then inserting the tabs 39 and 32 of the door plate 37 and jamb plate 30, respectively, into the separating space between the door 50 and the door jamb 51. This position is best illustrated in Figs. 4 and 5 of the drawings. After making sure that the tabs 39 are against the edge of the door, the wheel bracket 41 is attached to the door by screws 52, and door plate 37 is secured to the door by screws 53, and the track bracket 12 is attached to the door jamb 51 by screws 54.

After the previous steps have been completed, the track is then disengaged from the remainder of the assembly by removing the tape 23 and spacer block 22 and by removing the bolt 14 and spacer block 13. The next step is then to attach the jamb plate 30 to the door jamb 51. The bolt 34 and nut 35 holding the door plate 37 and jamb plate 30 are first loosened to permit adjustment and, after making sure that the tabs 32 are against the edge of the door jamb, the jamb plate 30 is secured in place by screws 60. The bolt 34 and nut 35 can then be removed. The arm supporting bracket 24 at the lower end of arm 21 is then secured to the door as by screw 61 and the jamb bracket is then secured to the door jamb 51 by screws 64. The lower end of the track can then be swung up until it is level and it is then attached to the ceiling as by the strap 65, as illustrated in Fig. 6 of the drawings.

In the final installation, the lower end of spring 18 is attached to a flange 66 on the door arm 21 but this preferably is not done until the door is in the up position which places the spring in its untensioned position. Accordingly, this step and adjustment of the spring tension are postponed until the pre-installation assembly for the left-hand side of the door is secured in place in a similar manner and the door can be moved to the open position.

It thus will be seen that there has been provided in accordance with the invention a pre-installation assembly for the mounting of a swing-up door which not only is a self-supporting rigid structure suitable for easy handling and shipping but which also provides a simple, easy and effective arrangement for properly locating and retaining the parts during installation whereby an accurate installation with a minimum of manpower and instruction can be readily attained.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim:

1. A pre-installation assembly of the mounting means for a swing-up door comprising an elongated channel-shaped steel track, a mounting bracket for the track pivotally connected to one end thereof, an elongated door plate having a projection at one end for engagement with the top of a door, said door plate extending parallel to the track with said one end adjacent the said mounting bracket, a wheel and support therefor mounted on said one end of the door plate with the wheel engaged in the track, an elongated jamb plate extending parallel to the track having its upper end detachably connected to the lower end of the door plate, a door arm extending parallel to the track, an elongated counterbalance spring extending parallel to the track, means pivotally connecting one end of the spring and one end of the arm to the jamb plate, and detachable means engaged with and re-

taining the door arm, counterbalance spring and jamb plate in parallel relationship with the track.

2. A pre-installation assembly of the mounting means for a swing-up door comprising an elongated channel-shaped steel track of approximately door length, a mounting bracket for the track pivotally connected to one end thereof, an elongated door plate adapted to position on an upper corner of the door in overlapping relationship with the door jamb, said door plate extending parallel to the track with one end adjacent the said mounting bracket, a wheel and support therefor mounted on said one end of the door plate with the wheel engaged in the track, an elongated jamb plate detachably connected to the lower end of the door plate and extending parallel to the track, said jamb plate being adapted to be secured to the door jamb in overlapping relationship with the side of the door, a door arm having means at one end for attachment to the lower end of the door, means pivotally connecting the other end of the door arm to the jamb plate, and means detachably connecting the jamb plate and the door arm to the track and maintaining the same in parallel spaced apart relationship relative to the track.

3. A pre-installation assembly of the mounting means for a swing-up door comprising an elongated channel-shaped steel track, a mounting bracket for the track pivotally connected to one end thereof, an elongated door plate having a projection at one end for engagement with the top of a door and longitudinally spaced projections for engagement with the side of a door, said door plate extending parallel to the track with said one end adjacent the said mounting bracket, a wheel and support therefor mounted on said one end of the door plate with the wheel engaged in the track, an elongated jamb plate extending parallel to the track having one end detachably connected to the lower end of the door plate, said jamb plate having longitudinally spaced projections for engagement with the side of a jamb, a jamb bracket fixed to the jamb plate, a door arm pivotally attached at one end to the jamb bracket and extending parallel to the track, an elongated counterbalance spring attached at one end to the jamb bracket and extending parallel to the track, and detachable means engaged with and retaining the door arm and counterbalance spring and the jamb plate in parallel relationship with the track.

4. A pre-installation assembly of the mounting means for a swing-up door comprising an elongated channel-shaped steel track of approximately door length, a mounting bracket for the track pivotally connected to one end thereof, an elongated door plate having a projection at one end for engagement with the top of a door and longitudinally spaced projections for engagement with the side of a door, said door plate extending parallel to the track with said one end adjacent the said mounting bracket, a wheel and support therefor mounted on said one end of the door plate with the wheel engaged in the track, an elongated jamb plate extending parallel to the track having one end detachably connected to the lower end of the door plate, said jamb plate having longitudinally spaced projections for engagement with the side of a jamb, a jamb bracket fixed to the jamb plate, a door arm pivotally attached at one end to the jamb bracket and extending parallel to the track, an elongated counterbalance spring attached at one end to the jamb bracket and extending parallel to the track, a pair of removable spaced means disposed respectively between and extending laterally of the track and the door arm and the track and the jamb bracket, and a pair of removable fastening means respectively engaging the door arm, counterbalance spring and track and the jamb bracket and track for preventing lateral separation of the door arm, counterbalance spring and jamb bracket from the track.

5. A pre-installation assembly of the mounting means for a swing-up door comprising an elongated channel-shaped steel track, a mounting bracket for the track pivotally connected to one end thereof, an elongated door plate having an inwardly turned flange at one end for engagement with the top of a door and longitudinally spaced projections for engagement with the side of a door, said door plate extending parallel to the track with said one end adjacent the said mounting bracket, a wheel and support therefor mounted on said one end of the door plate with the wheel engaged in the track, an elongated jamb plate extending parallel to the track having one end abutting the lower end of the door plate and offset laterally therefrom, said jamb plate having longitudinally spaced projections for engagement with the side of a jamb, detachable means forming a temporary connection between the abutting ends of the plates, a jamb bracket fixed to the jamb plate, a tem-

porary rigid connection between the jamb bracket and the track comprising a removable spacer block and a removable bolt, a door arm pivotally attached at one end to the jamb bracket and extending parallel to the track, an elongated counterbalance spring attached at one end to the jamb bracket and extending parallel to the track, and means for retaining the door arm and counterbalance spring in parallel relationship with the end of the track comprising a removable spacer block between the arm and the track and a removable tape encircling the track, spacer block, door arm and spring.
